UNITED STATES PATENT OFFICE.

EDMOND F. STRATTON, OF NEW YORK, N. Y.

DESIGN FOR A CASING FOR SHOE-POLISHING MACHINES.

No. 39,571.

Specification for Design.

Patented Sept. 22, 1908.

Application filed May 18, 1908. Serial No. 433,618. Term of patent 7 years.

To all whom it may concern:

Be it known that I, EDMOND F. STRATTON, a citizen of the United States, and a resident of the city of New York, county and State of New York, have invented a new, original, and ornamental Design for a Casing for a Shoe-Polishing Machine, of which the following is a specification, reference being had to the accompanying drawing, forming part thereof.

The figure represents a view in perspective of a casing showing my new design.

Upon a stand or base 1 is mounted an upright casing 2, rectangular and slightly de-

creasing in width from the base up. Adjacent the bottom of the casing are hoods 3. An ornamental plate 4 is secured to the top of the casing at the front, while a second plate 5 is placed at the front of the casing adjacent the top.

I claim:

The ornamental design for a casing for a shoe polishing machine, as shown and described.

EDMOND F. STRATTON.
